UNITED STATES PATENT OFFICE.

JOHN C. McLACHLAN, OF BRANTFORD, ONTARIO, CANADA, ASSIGNOR TO
A. HARRIS SON & CO., OF SAME PLACE.

HARVESTING-MACHINE.

SPECIFICATION forming part of Letters Patent No. 242,833, dated June 14, 1881.

Application filed January 25, 1881. (No model.)

To all whom it may concern:

Be it known that I, JOHN CAMPBELL MC-LACHLAN, of the city of Brantford, in the county of Brant, in the Province of Ontario, Canada, have invented new and useful Improvements in Harvesting-Machines, of which the following is a specification.

The invention relates to certain improvements in the mechanism employed for raising and tilting the finger-beam, and also in the general construction of the machine, as hereinafter explained.

Figure 1 is a perspective view, exhibiting the portions of my machine to which my improvements relate. Fig. 2 is a detail showing a portion of the frame and table with the tilting lever and grain-wheel-adjusting lever. Fig. 3 is a detail showing the formation of the pulley for carrying the grain-wheel-lifting chain. Figs. 4 and 4^a are details showing a portion of the frame and tongue with the tilting-lever and grain-wheel-adjusting lever. Fig. 5 is an end view of the grooved ratchet-sheaf employed with the lifting-lever. Figs. 6 and 6^a are details of the grain-wheel arm and connections. Fig. 7 is a detail, showing manner of connecting the chain to the grain-wheel arm.

In the drawings like letters indicate corresponding parts in each figure.

A is the main frame of the machine; B, the pole, provided with a pole-block, C, made to form one member of the hinge D, which connects the pole to the main frame A.

E is a tilting-lever bolted to the flange c' of the pole-block C, as indicated in Fig. 4. The tilting-lever E extends back to within easy reach of the driver's seat F, and is provided with the ordinary hinged rack, G.

H is a ratchet-pawl hinged to the tilting-lever E, and made to engage with the ratchet-teeth on the grooved ratchet-sheaf I. This pawl H has a circular slot, h, through which the bent end of the lifting-rod i passes (see Figs. 4 and 5) to the lever J, where it enters a vertical slot, e, in the said lever, and is secured thereto by a nut and washer or other suitable means. The lifting-rod i is connected to the upper end of the lever J by the ordinary pivoted band-plate, f, and is arranged, as described, for the purpose of lifting the pawl.

J is the grain-wheel-adjusting lever pivoted to the tilting-lever E, as shown.

I have mentioned that the ratchet-pawl H is pivoted to the tilting-lever E. This would probably answer the purpose; but a more mechanical way of putting them together is shown in the drawings. It consists of a casting, K, provided with a long hub or sleeve, upon which the ratchet-sheaf and lever J are slipped and held in position by the bolt L. The casing K forms at the same time a projection, to which the pawl H is fastened, as represented.

It will be noticed in Figs. 4 and 5 that the inside face of the ratchet-sheaf I is provided with a circle of projecting stop-blocks, M. These blocks are placed in the position shown for the purpose of connecting the lever J to the ratchet-sheaf I, as will be understood by examining the figures referred to, particularly Fig. 5, in which it will be seen that the lever J can be pressed against the ratchet-sheaf I, as shown in dotted lines, so as to come in contact with the blocks M, or may be withdrawn therefrom, as shown in the full lines of this figure. When so withdrawn this lever works freely on its pivot, the slot h in the pawl H permitting the movement. It may be mentioned here that by passing the lifting-rod i through this slot the pawl H can be lifted, no matter at what angle the lever J may at the time be. A chain, N, is secured in the ordinary way to the ratchet-sheaf I, and extends back over the pitman-head, where it passes over pulleys O and P, shaped as shown in Fig. 3, the pulley O being held in the casting which covers the pitman to the pulley P at the bottom of the rake-jack stand. Their relative position is clearly shown in Fig. 2. From the pulley P the chain extends to the grain side of the table Q, where it passes over another pulley, similar to O and P, and extends up to the grain-wheel arm R, as shown in Fig. 6. In order to secure the chain N to the grain-wheel arm, I employ an eye-pin, S, which passes through a hole in the flange r in the grain-wheel arm, and is held there by the clamp T.

It will be noticed on reference to Figs. 6 and 7 that the chain N passes up behind the grain-wheel arm in a recess, r', therein, (see Fig. 6,) and is connected to the eye-pin S on the top wheel-arm. By this connection it will be seen

that the weight of the machine holds the pin in position.

On reference to Fig. 6 it will be noticed that the point of the casting U to which the grain-wheel arm is pivoted is formed into a wedge-shaped shield, V, extending over the cutter-bar. This shield not only protects the end of the cutter-bar from the dirt which would otherwise be thrown on it from the grain-wheel, but also serves as a guard to divide the grain and keep it clear of the grain-wheel.

From the drawings it will be seen that my invention relates to that class of harvesting-machines having a lever-seat arranged to adjust the inside of the machine, and in which the finger-beam is bolted rigidly to the main frame carrying the cutting apparatus, crank-head, and connecting-rod, so that all these parts retain their relative position when the cutting apparatus is adjusted. As this form of construction is well understood, it is not necessary to enter into an explanation of this part of the machine. It will, however, be seen that the driver on the seat F can, by seizing the tilting-lever E, raise the inside of the machine and by the same lever tilt the guards up or down to gather lodged grain, and at the same time impart, in a measure, a vertical adjustment to the outside of the machine. By bolting a metallic frame, W, to the finger-beam and to the frame the connection between the tongue and finger-bar is very much strengthened. This metallic frame has a hinge, w, as shown, to which the diagonal brace W' is connected. This connection permits the free adjustment of the machine without affecting the connection of the diagonal brace to the tongue, and very much strengthens this portion of the machine.

Having now described the general construction of that part of the machine to which my improvements relate, a few words will suffice to explain their operations.

As the grain-wheel-adjusting chain connects the grain-wheel arm R to the ratchet-sheaf I, any movement of this ratchet-sheaf raises or lowers the grain-wheel side of the machine. In order to raise the grain-wheel side of the machine, the driver presses the adjusting-lever J against one of the blocks M, and, drawing upon it, causes this sheaf to revolve on its center, thereby drawing up the chain and raising the grain-wheel side of the machine as desired. In order to take hold of the next block M, the lever J is pushed over the sheaf, as indicated in Fig. 5, when it can be thrown forward freely and a fresh block seized, repeating the operation till the grain-wheel side of the machine is raised as far as desired. When the grain-wheel side of the machine is to be lowered the lever J is pressed against one of the blocks M sufficiently to take the pressure off the pawl H, when the lifting-rod can be pressed up and the pawl raised. The lever J is then pushed forward and the chain N "paid out," so as to allow the grain-wheel side of the machine to

fall as desired. If it is necessary to let this side of the machine down farther than the slot h permits, the pawl H is allowed to engage with the ratchet-teeth, and the lever J, being thrown clear of the block it may be pressing against, is drawn back to the next block.

The construction is shown so clearly in the drawings that it is hardly necessary to mention here that moving the tilting-lever to tilt the machine imparts a vertical adjustment to the grain-wheel side of the machine, owing to the fact that the chain N connects this lever to the grain-wheel arm, as shown.

From the fact that the lever J is pivoted upon the tilting-lever it will be seen that the grain-wheel side of the machine can be adjusted without affecting the inside.

As shown in Fig. 3, it will be seen that the chain-pulleys O and P are formed so that the chain shall lie perfectly flat on the said pulley, a groove being cut to receive the link passing edgewise over the pulley, which permits the link lying flat to rest on the flanges of the pulley on either side of the said groove.

What I claim as my invention is—

1. In harvesting-machines, a tilting-lever rigidly connected to the hinged pole or tongue of the machine, in combination with the grain-wheel-adjusting chain, so arranged that in tilting the machine the movement of the tilting-lever imparts simultaneously a vertical adjustment on the grain-wheel side of the machine.

2. In harvesting-machines, a tilting-lever rigidly connected to the hinged pole or tongue of the machine, in combination with a grain-wheel-adjusting lever pivoted on the tilting-lever, and so connected to the grain-wheel that a vertical adjustment can be imparted to the grain-wheel side of the machine without affecting the inside.

3. In harvesting-machines, a ratchet-sheaf pivoted to the tilting-lever, and having attached to it the grain-wheel-adjusting chain, in combination with a ratchet-pawl pivoted to the tilting-lever and operated by the grain-wheel-adjusting lever, substantially as and for the purpose specified.

4. In a harvesting-machine having a lever-seat arranged to adjust the inside of the machine, a tilting-lever rigidly fastened to the hinged tongue or pole of the machine, in combination with a rack-bar connected to the main frame of the machine, and a chain connecting the tilting-lever to the grain-wheel, substantially as described.

5. In a harvesting-machine, a chain, N, attached to the grain-wheel arm R and passing over the grooved pulley P, located at the base of the rake-jack stand, and grooved pulley O on the pitman-head cover, in combination with the ratchet-sheaf I, pivoted on the tilting-lever E, and operated by the lever J, substantially as and for the purpose specified.

6. The combination, with the cutter-bar, of the casting U, terminating in a wedge-shaped flange, shield V, extending over the outer end

of the cutter-bar, and forming a grain-divider, and grain-wheel arm R, pivoted to said casting, substantially as described.

7. The combination, with the pivoted grain-wheel arm R, provided with a recess, r' , and flange r , similarly recessed, of the eyebolt S, passing through a hole in the flange, clamp T, and chain N, substantially as described, and for the purpose set forth.
- 10 8. In a harvesting-machine, a pawl, H, pivoted to the tilting-lever E, and having a slotted passage-way, h , cut in it, as shown, in combination with the lifting-rod i connected to the lever J, as described, and operated for the purpose of throwing the pawl in and out of gear.

9. In a harvesting-machine, a grain-wheel-adjusting chain, N, connected to the ratchet-sheaf I, pivoted on the tilting-lever E, and prevented from revolving in one direction by the slotted pawl H, with blocks M on the face of the said sheaf, in combination with the lever J, pivoted to the tilting-lever E on the same center as the sheaf I, and provided with a lifting-rod, i , passing through a slot, h , in the pawl H, and secured to the lever J, substantially as and for the purpose specified.

JOHN CAMPBELL McLACHLAN.
